CLAIM

The ornamental design for a display screen or portion thereof with animated icon providing a measurement value display, as shown and described.

DESCRIPTION

The patent or application file contains at least one drawing executed in color. Copies of this patent or patent application publication with color drawing(s) will be provided by the Office upon request and payment of the necessary fee.

1.1 : is a first image in a sequence of a display screen or portion thereof with animated icon providing a measurement value display showing our new design in a first embodiment;

1.2 : is a front view of a second image thereof;

1.3 : is a front view of a third image thereof;

1.4 : is a front view of a fourth image thereof;

1.5 : is a front view of a fifth image thereof;

1.6 : is a front view of a sixth image thereof;

1.7: is a front view of a seventh image thereof;

2.1 : is a first image in a sequence of the display screen or portion thereof with animated icon providing a measurement value display showing our new design in a second embodiment;

2.2 : is a front view of a second image thereof;

2.3 : is a front view of a third image thereof;

2.4: is a front view of a fourth image thereof;

(Continued)

2.5 : is a front view of a fifth image thereof;
 2.6 : is a front view of a sixth image thereof;
 2.7: is a front view of a seventh image thereof;
 The appearance of the transitional image sequentially transitions between the images shown in 1.1-1.7 and 2.1-2.7. The process or period in which one image transitions to another image forms no part of the claimed design. No ornamental aspects are associated with the process or period in which one image transitions to another image. The broken line showing a display screen depicts environmental structure that forms no part of the claimed design.
